OIL FILTER

James E. Hurn, Saugerties, N. Y., assignor to
The De Luxe Products Corporation, La Porte,
Ind.

Application April 27, 1935, Serial No. 18,546

4 Claims. (Cl. 210—131)

My invention is an oil filter, and is a full-flow filter having a special adaption to the type of engine capable of using a low grade oil, such as in a Diesel engine.

5 Its leading object is the provision of a primary element for taking the full-flow of oil and filtering out abrasive and non-lubricating elements prior to a complete purifying process.

This invention is an improvement of, and based 10 upon my application S. N. 702,529; filed December 15, 1933, and includes the fundamental principles therein.

The accompanying drawing exhibits an embodiment of my invention, in which

15 Fig. 1 is a sectional elevation of the device showing the internal working arrangement.

Fig. 2 is a cross section on the line 2—2 taken in the direction of the arrow.

Fig. 3 is a vertical section taken along the line 20 3—3, in the direction of the arrows.

Fig. 4 is a modified form of a sludge outlet.

As illustrated, 1 is the housing of the device; 2 is the cover for enclosing the top opening; 3 is a shoulder internal of housing; 4 is a sump portion tributary to the filtering means thereabove; 5 is a tubular member fixedly seated in the center of the housing; threaded at 6 in a tubular channel member 1; 8 is a revolvable nut or plug set in the cover, having a bar means 9 to rotate 30 the same for locking the cover to the housing, it having a threaded extension 10 for fitting into the tubular member 5; 8' is a shoulder on said plug adapted to co-act with a gasket 8'' to seal the cover when the parts are locked together. 11

35 8 is a shoulder on plug 8 adapted to position a crown member 12 on a filtering unit; 13 is a nut threaded on the extension 10 and adapted to lock the crown 12 to the same enabling it to be lifted out when the cover is released with the plug. A bore 14 extends longitudinally thru the plug there being a portion 18 of the bore of smaller diameter than the outer portion, the junction of the two diameters of the bore forming a valve seat 19, upon which valve seat rests a ball valve 16, tensioned by a spring 16, and regulatable by a tension nut 17. The diameter of the bore 18 is of equal diameter with a nozzle aperture 6' in the channel member 7. A lateral bore 19' from one

40 side of the plug 8 to an opening into 14, forms a release to excess pressure. 20 are perforations in the wall of the tubular member 5, substantially midway of its height and adjacent to the blank walls of a member 23 to be hereinafter described. 21 is a base—preferably metal—of a

demountable filtering unit; this base has its periphery 22 slightly less than the diameter of the housing chamber and bent to an upturn adapted to be seated upon a ridge above the sump 4; this base portion 21 is centrally drawn up into a 5 cone-shape 23 to a height substantially midway of the filtering unit, the apex of the cone adapted to snugly encircle the tubular member 5—there being a slight flare 23' of the apex opening of the filtering structural member 21. I provide a 10 plurality of perforations 25 in the conical wall 23 encircling the cone at its lower extremity, the upper of said perforations being spacedly below the perforations 20 in tube 5. I provide a member 26 penetrating and supporting a filtering element, the said supporting member having its base resting upon the base of the cone 23. I provide a filtering bag formation 24 having a flange to extend around and under the up-turned edge 22 of the base 21, the upper portion of the said 20 bag 24 having an internal columnar portion 24'' adapted to extend inwardly of the filtering unit to contact and co-act with the flared opening 23' of the apex of the cone; and I provide a locking device 28 to contact 23' and 24' thus forming a 25 substantially sealed filtering unit. Into this formation of the conical member 21, 23, and the bag formation 24, I place a dense amorphous mass 27 of soft absorbent and adsorbent material. I provide an outlet opening 30 in the upper 30 wall of the housing 1 communicating with a channel 31 leading to an opening 32 communicating with the crankcase.

The member 1 into which tube 5 is threaded has an extension 1' which threads into a portion 35 of the housing at 34, there being in this portion of the housing an inlet opening 35 having communication under certain conditions hereinafter described to a common point 36. The inlet 35 being adapted to primarily provide for the passage of the oil under pressure to a primary filtering structure hereinafter described, there being provided a means to permit the passage of the incoming oil in one direction to point 36 and thence to the filtering element heretofore described: or in the event that the primary filtering element hereinafter described becomes clogged or rendered otherwise incapacitated then a valve 39 operable in a channel 38, tensioned by a spring 40 and a nut 41, releases under pressure and feeds directly into 36 from there. 42 is a plug enclosing the release valve mechanism. 43 is a channel leading from the entry channel 35 directly into a chamber 4'. In the chamber 4' 55

there is suspended a series of concentric filtering elements 44, there being open spaces 45 for the passage of oil up thru said spaces into contact with the walls of the depending concentric filters: each said depending filter consists of a pair of concentric foraminous walls 46 enclosing an insert 46' adapted to maintain the integrity of the member and the relation of the walls to each other and prevent collapse of the walls under pressure; these foraminous dependents are attached to a supporting bracket 47 which said bracket bears a multiplicity of apertures 48 providing passage from the chamber of each depending member 44 to an area 50 which area 15 communicates thru a plurality of apertures 50' into the chamber of 7' whence the oil may pass out either thru 37 to the engine bearings or thru a nozzle 6' into the tube 5. The bracket 47 is supported on a shoulder 3 in the body of the housing, and seated upon this bracket support of 47 I provide a disc 49 as a divisional means between the primary full-flow filter and the upper purifying filter. 51 is an outlet for the removal of sludge ingredients from the sump 4 and 52 is 20 a release plug in 51. 57 is an attaching plate, 58 is a threaded aperture in the sump 4' whereby to release sludge accumulation and is located in a boss 59.

In Fig. 4 I show a modification of the releasing means of accumulation in sump 4 which consists in an aperture 55 in disc 49, registering with a conduit 56 and an aperture 56' in a chambered nut 54, which said nut has at its inner end a valve 53 so balanced that it will be automatically closed during the operation of the engine and automatically opened by the weight of sludge when the engine is at rest.

In connection with this type of filter it will be recognized that in connection with the engine (which is not shown) there is a pump pumping the oil from the reservoir supply and doing it at varying pressures and volumes, and somewhere in the line between the pump and the point of connection with the filter there is an automatic valve provided to release when the pressure is above a given factor, so that the oil coming in at the entrance of 35 is substantially of uniform pressure. Assuming that condition, the operation of the filter is as follows:

The oil under pressure entering the channel 35 and passing up thru conduit 43 comes into contact with the primary filtering elements 44—having a broad contact in the channels 45—filters thru the foraminous major portions of 46, passing from the same, delivered of its heavier deleterious products, thru the apertures 48 into the area 50, thence thru the apertures 50' into the chamber of 7'; a minor portion passing down the chamber to the point 36 and thence thru 37 to the bearings of the engine; and a portion passing thru the constricted aperture 6' into the chamber of 5 where it is emulsified under a given pressure regulated by the valve 15; from this chamber it is forced thru the apertures 20 against the blank walls of the cone at 23 and atomized, while at the same time, a distinct sharp change in direction of flow is had downward into an expanding cone, during which time it precipitates the heavier elements and the lighter portion of the oil passes laterally thru the apertures 25 in the cone 23 and thence, by capillary attraction, upward thru 21, being cleansed by absorption and adsorption; passing out thru 30 as clarified oil back to the crankcase. In the event the primary filter portions 44 become clogged the pres-

sure of the oil moves the piston 38, whence the oil feeds directly into 36, one portion going directly to the bearings and the other portion going up thru the purifying filter.

As heretofore set forth, the invention is primarily applicable to an engine such as the Diesel engine in which low grade oils are customarily employed. Such oils frequently oxidize with great rapidity or form large bodies of oxidized or non-lubricated impurities which it is not desirable to return to the bearings. Therefore, in such an engine the device shown in my co-pending application 702,529, filed December 15, 1933, which filters a small portion of the oil only, but filters it so thoroughly that the entire body of the oil is continually maintained in a suitable state of cleanliness, is not so satisfactory as it is upon better grades of lubricating oil.

The foregoing detailed description has been given for clearness of understanding only, and no unnecessary limitations should be understood therefrom, but the appended claims should be construed as broadly as permissible in view of the prior art.

I claim:

1. In a device of the class described the combination with an internal combustion engine of an oil purifying device consisting of a housing having inlet and outlet means adapted to register with inlet and outlet channels communicating with the crankcase of such an engine; there being in said housing two chambers, one above the other, having a dividing wall between the said chambers; a tubular member vertically axial of the housing and the two chambers, there being a constricted aperture in the said tubular chamber approximately along the line of the dividing wall; in the lower chamber a series of concentrically arranged screens dependently attached to a bracket providing free oil space between the bracket and the lower side of the dividing wall; open channels from the screen members into the said open space; apertures from the open space into the central tubular member below the dividing wall; the inlet to the housing from the engine being into the lower chamber there being an outlet direct into the said screen chamber, and a valve controlled connection with the tubular member; a sump in the screen chamber; an outlet from the tubular member to the crankcase of the engine; an outlet from the sump in the screen chamber; the upper chamber containing a sump, and assembled above the said sump a filtering cartridge consisting of a base having a conical member extending upward from the said base and an amorphoused mass of filtering material confined within a foraminous sack, the said cartridge suspended around the tubular member; apertures in the wall of the tubular member within the confines of the conical portion of the filtering cartridge; a cover for the housing having locking means coacting with the tubular member to lock the housing and its contents into a unit; a valve with tensioning element assembled in the locking member adapted to determine the pressure in the portion of the tubular member in the upper filtering chamber; an outlet from the filtering chamber to the crankcase of the engine; an outlet from the sump in the upper chamber.

2. In combination with an internal combustion engine, a device for screening and purifying lubricating oil during operation of the engine, comprising a housing having a first and second chamber divided from each other, a tubular con-

duit extending into both chambers and having an opening to each, an inlet from the oil reservoir of the engine communicating with the tubular conduit and having a separate opening 5 into the first chamber, pressure controlled means for controlling entry of oil from the inlet to the tubular conduit, an outlet from the first chamber communicating through the tubular conduit to the bearings, an oil screening device in the first chamber between the inlet and outlet, an oil filtering means in the second chamber, and an outlet from said chamber communicating with the oil reservoir of the engine.

10 3. A device as set forth in claim 2 in which means are provided within the tubular conduit for limiting the flow of oil to the filtering means.

15 4. In combination with an internal combustion engine, a device for screening and purifying

lubricating oil during operation of the engine, comprising a housing having a first and second chamber divided from each other, a tubular conduit communicating with both chambers, an inlet from the oil reservoir of the engine communicating 5 with the tubular conduit and having a separate opening into the first chamber, pressure controlled means for controlling entry of oil from the inlet to the tubular conduit, an outlet from the first chamber communicating 10 through the tubular conduit to the bearings, an oil screening device in the first chamber between the inlet and outlet, an oil filtering means in the second chamber, and an outlet from said chamber communicating with the oil reservoir of the 15 engine.
